CLAIM

The ornamental design for rectangular compression latch, as shown and described.

DESCRIPTION

FIG. 1 is a top front right isometric view of the rectangular compression latch of the invention, in its closed position.

FIG. 2 is a top view of the rectangular compression latch of FIG. 1.

FIG. 3 is a right side view of the trigger latch of FIG. 1, the left side view being a mirror image;

FIG. 4 is a front view of the rectangular compression latch of FIG. 1.

FIG. 5 is a rear view of the rectangular compression latch of FIG. 1.

FIG. 6 is a top front right isometric view of the rectangular compression latch of FIG. 1 of the invention, but in its opened position.

FIG. 7 is a top view of the rectangular compression latch of FIG. 6.

FIG. 8 is a right side view of the trigger latch of FIG. 6, the left side view being a mirror image;

FIG. 9 is a front view of the rectangular compression latch of FIG. 6; and,

FIG. 10 is a rear view of the rectangular compression latch of FIG. 6.

The broken lines shown in the drawing disclosure are for illustrative purposes only and form no part of the claimed design.
